US0D1065056S

(12) **United States Design Patent** (10) **Patent No.:** **US D1,065,056 S**
(45) **Date of Patent:** **** Mar. 4, 2025**

(54) **BATTERY**

(71) Applicant: **Lion Energy, LLC**, American Fork, UT (US)

(72) Inventors: **Tyler Hortin**, American Fork, UT (US); **Thierry Caussat**, American Fork, UT (US); **Timothy Nelson**, American Fork, UT (US)

(73) Assignee: **Lion Energy, LLC**, American Fork, UT (US)

(**) Term: **15 Years**

(21) Appl. No.: **29/868,109**

(22) Filed: **Nov. 18, 2022**

(51) LOC (15) Cl. **13-02**

(52) U.S. Cl.

USPC **D13/104**

(58) **Field of Classification Search**

USPC D13/104, 107, 103, 110, 112, 118, 119, D13/184, 199, 106, 108, 102

CPC Y02T 90/14; Y02T 90/163; Y02E 60/12; H02J 7/0044; H02J 7/0045; H02J 7/00

(57) **CLAIM**

The ornamental design for a battery as shown and described.

DESCRIPTION

FIG. 1 is a front perspective view of a battery of our new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

In the drawings, the broken lines are for the purpose of illustrating portions of the battery that form no part of the claimed design.

1 Claim, 4 Drawing Sheets
